ABSTRACT

A golf club cleaning device including an upwardly open receptacle containing washing liquid. A shaft transversely journaled by the upper edge portions of opposing walls of the receptacle is provided with scrubbing brushes and a fabric buffer. An electrical resistance heating element heats the washing fluid.

GOLF CLUB CLEANER

BACKGROUND OF THE INVENTION

1. Field of the invention.

The present invention relates to a cleaning apparatus and more particularly to a golf club cleaning and drying apparatus.

It is important, from the view point of proficiency, in playing golf that the golf club heads be maintained in a clean state free from soil or grime. It is also important that the golf clubs be cleaned after each use to eliminate the presence of dirt in the grooves of irons to prevent certain chemicals in soils inducing corrosion or rusting and consequent pitting of the club head surface. Furthermore, a greater stability and control of a golf ball flight may be achieved when using a golf club which has been properly cleaned.

It has been common practice to use a cleaning fluid and a hand brush for cleaning golf clubs but this is, at best, a slow and tedious operation.

2. Description of the prior art.

Golf club cleaning devices are disclosed by U.S. Pat. Nos. 3,148,396; 3,332,099; 3,400,416 and 3,412,414 wherein the head is inserted into the apparatus through an opening therein for the cleaning action wherein the actual cleaning action cannot be observed while in progress.

This invention, on the other hand, provides an open-type cleaner wherein the user may manually position the golf club head against selected ones of a plurality of brushes to observe the cleaning action while in progress and supplement the cleaning action by the emersion of the club head in the cleaning fluid as may be necessary thus avoiding any damage to the surface of the golf club head whether it be an iron or wood. Furthermore, the components used in this invention are readily available and the simplicity of construction renders the cleaning device inexpensive in initial cost and operation.

SUMMARY OF THE INVENTION

A stand supported upwardly open receptacle is provided with a golf club handle contacting resilient padding on its upwardly disposed rim. A shaft is transversely journaled by the receptacle near its upper limit. A plurality of brushes, mounted on the shaft in spaced-apart relation, are rotated with the shaft by a motor supported by the stand. An electrical resistance heating element is positioned within the receptacle below the level of the cleaning fluid therein.

The principal object of this invention is to provide a golf club head washing and drying device.

BRIEF DESCRIPTION OF THE DRAWINGS

FIG. 1 is a front elevational view of the device with a portion of the receptacle wall broken away for clarity;

FIG. 2 is a top view of FIG. 1; and,

FIGS. 3 and 4 are left and right side views, respectively of FIG. 1.

DESCRIPTION OF THE PREFERRED EMBODIMENT

Like characters of reference designate like parts in those figures of the drawings in which they occur.

In the drawings:

The reference numeral 10 indicates the device, as a whole, comprising an upwardly open rectangular receptacle 12 having its bottom wall 13 resting on a stand 14. The receptacle 12 includes a front wall 16 joined to a backwall 18 by sidewalls 20 and 22. The top of the receptacle is partially closed by a top wall 24 joined to the backwall 18 and the rearward portion of the sidewalls 20 and 22. The sidewalls 20 and 22, forwardly of the forward limit of the top wall 24, are angled or beveled downwardly to form an incline, as indicated at 26, terminating in the plane of the upper limit of the forward wall 16. Thus the horizontal plane of the upper edge of the forward wall 16 is spaced below the horizontal plane of the top wall 24 for ease in manipulating a golf club, not shown, when cleaning the club, as hereinafter described.

5 The forwardly declining upper edges 26 of the sidewalls and the upper limit of the front wall 16 is covered by a resilient material, such as rubber, or the like, to form a strip of padding 28 to prevent damage to the surface of a golf club handle, or the like, while being cleaned.

10 The top wall 24 is provided with an opening 30 open toward its forward edge which is covered by a hood or splash guard 32 secured to the top wall around its edges defining the opening 30. The guard 32 is characterized by a top wall 34 which is inclined upwardly and forwardly of the forward edge of the top wall.

15 An elongated shaft 36 projects transversely through and beyond the sidewalls 20 and 22 adjacent their upper limit and in spaced relation with respect to the forward edge portion of the top wall 24. Bearings 38, connected with the respective sidewall, journal the shaft. A stiff bristle cleaning brush 40 is coaxially secured to one end of the shaft. Similarly a washing and scrubbing brush 42, preferably a bristle brush, is coaxially 20 connected to the shaft medially its ends and in spaced relation with respect to the inner surface of the guard 32. A buffer and polisher 44, comprising a plurality of diametrically equal layers of fabric, or the like, is coaxially secured to the opposite end portion of the shaft 36.

25 A motor 46, having a drive shaft 48, is secured to a motor mount 50, connected with and supported by the stand 14 adjacent the lower limit of the rearward wall 18. Belt and pulley means 52 is connected with the shaft 36 and drive shaft 48 for rotating the brushes and fabric buffer.

30 An electrical resistance heating element 54 is positioned within the receptacle 12 in spaced relation with respect to its sidewalls and bottom 13 below the level of a quantity of cleaning liquid 56 contained by the receptacle. A source of electrical energy AC is connected to a junction box 58 and in turn connected with the motor 46 and heating element 54 by wires 60 and 62, respectively. Obviously a thermostat, not shown, may be used to control the temperature of the washing liquid if desired. Current to the motor and heating element is controlled by switches 64 and 66, respectively.

OPERATION

35 In operation the washing liquid 56, containing a suitable detergent or soap, if desired, is heated by the heating element 54 to a desired temperature. A golf club to be cleaned, not shown, having an excess of dirt or grime clinging to its head, or other portions thereof, is manually positioned against the rotating cleaning brush 40 to remove such excess of soil. The 40 golf club head is then further cleaned to remove all dirt and grime by dipping the head into the cleaning fluid 56 and positioning the head against the lowermost peripheral surface of the scrubbing brush 42. During this cleaning action the padding 28 prevents damage, such as scratching, to the golf club handle portion. The golf club head may be forcibly positioned against the scrubbing brush 42 by resting an intermediate point of the golf club handle on the padding 28 which acts as a fulcrum point when the handle held end of the golf club is moved downwardly. This action is repeated until the golf club appears cleaned which is then dried and buffed or polished by manually positioning it against the rotating periphery of the fabric buffer 44.

45 Obviously the invention is susceptible to changes or alterations without defeating its practicability, therefore, I do not wish to be confined to the preferred embodiment shown in the drawings and described herein.

I claim:

50 1. A golf club cleaner, comprising:
an upwardly open generally rectangular washing liquid containing receptacle having a front wall and a back wall joined with opposing sidewalls,
said front wall having an upper edge lying in a horizontal plane spaced below the plane of the upper limit of the backwall,

said receptacle having a rectangular top wall horizontally overlying and secured to said backwall and a portion of the upper edge of the sidewalls adjacent the backwall, the upper edge of each sidewall forwardly of the forward edge limit of the top wall being inclined forwardly and downwardly and merging with the upper edge surface of the front wall; 5
 a shaft journaled by and extending beyond, at its respective ends, said sidewalls adjacent their upper limit and the forward limit of said top wall, said top wall having an opening in its forward edge medially its length; 10
 a scrubbing brush coaxially secured to said shaft medially its ends; 15
 a splash guard secured to said top wall around the opening

therein and in overlying relation with respect to said scrubbing brush; a motor drivably connected with said shaft; a cleaning brush coaxially connected with one end portion of said shaft; a fabric buffer coaxially secured to the other end portion of said shaft; and, a section of resilient padding secured to the upper edge surface of said front wall and forming a fulcrum point for an intermediate portion of a golf club handle when the head portion thereof is disposed within the confines of said receptacle, whereby the golf club head portion may be steadily positioned against the depending peripheral portion of said scrubbing brush in a cleaning action.
